UNITED STATES PATENT OFFICE.

CHARLES D. McARTHUR, OF PITTSBURG, PENNSYLVANIA, ASSIGNOR TO BLOW COLLAPSIBLE STEEL CENTERING COMPANY, OF PITTSBURG, PENNSYLVANIA, A CORPORATION OF NEW JERSEY.

MOLD.

971,391.

Specification of Letters Patent. Patented Sept. 27, 1910.

Application filed February 4, 1910. Serial No. 542,066.

To all whom it may concern:

Be it known that I, CHARLES D. McARTHUR, a citizen of the United States, residing at Pittsburg, in the county of Allegheny and State of Pennsylvania, have invented certain new and useful Improvements in Molds, of which the following is a specification.

The invention relates to molds or forms for the construction of concrete sewers, conduits and similar passages, and particularly to the collapsible type employed in the construction of passages of relatively large diameter. The invention has for its primary objects; the provision of an improved form which may be readily collapsed and carried forward and positioned for re-use; the provision of a form having a lower or base portion which can be accurately positioned and held rigidly in place, and in which the bracing framework for the base serves as a support for the track on which the truck for carrying the collapsible upper section rides. One embodiment of the invention is illustrated in the accompanying drawings, wherein:—

Figure 1 is an end view of the form, and Figure 2 is a section taken on the line II—II of Figure 1 with the truck removed.

The mold or form is made in three parts, an upper arched portion, and a lower side portion at each side of the mold to which the lower edges of the arched section are secured. The framework of the upper arched portion consists of a series of ribs 1, 2, 3 and 4 (Fig. 2), each of which is in two parts hinged together at 5, and a supporting framework for each of the lower side portions of the mold consists of a series of ribs 6, 7, 8 and 9 arranged substantially in alinement with the ribs 1, 2, 3 and 4. To the outside of the channels a series of lagging plates 10 are riveted. Additional stiffness is given to the ribs 1 and 4 by means of stiffening ribs 11, 12, 13 and 13' riveted to the inner flanges of the channels as indicated in Figure 2. The channels 14 and 15, as shown in Figure 2, are the end ribs on other sections, such ribs being secured detachably to the ribs 1 and 4 by means of bolts (not shown). Wooden strips 17 and 18 are interposed between the angles 19 and 20 carried by the arched and side sections respectively, and the sections are maintained releasably in position by means of

the bolts 21. The lower edges of the side plates are spaced apart in fixed relation by means of a series of transverse beams 22, which beams are provided with the angle clips 23 resting against the clips 24 carried by the lower edges of the side sections. The beams are also supported by means of the struts 25 carried by the blocks 26 resting upon the floor of the conduit. The ends of the beams are also held in position by means of the turn-buckles 27 having their upper ends hooked detachably into the loops 28 carried by the side sections. The upper portions of the side sections are held securely in position by means of braces 29 whose ends are slotted and engage the loops 30 and 31 carried by the beams and side sections respectively, the parts being secured in position by means of pins (not shown). Upon the top of the beams 22 are the rails 32 which in turn carry the truck 33. This truck is provided with collapsing turn-buckles 34 and 35, and with a collapsing jack 36, so that the arched section may be collapsed when the bolts 21 are removed.

In operation the beams 22 and the side sections are first positioned and the concrete is applied therebehind, and then the truck 33 carrying the arched section is brought into position upon the track and mounted upon the strips 17, being secured in this position by means of the bolts 21. Concrete is then applied over the arched section. While this operation is proceeding another pair of side sections similar to the side sections shown are positioned and concrete applied therebehind, and when the concrete upon the arched section has set, this section is collapsed and carried forward and placed upon the side sections.

Having thus described my invention and illustrated its use, what I claim as new and desire to secure by Letters Patent is the following:—

1. In combination in a U shaped mold, a pair of lower opposing side sections, a series of transverse beams extending across the bottom of the mold arranged to hold the lower edges of the side sections in position, inclined braces for the side sections extending diagonally downward from such sections for maintaining the upper edges of the sections rigidly in position, a track mounted on the beams between the diagonal side braces, a self sustaining collapsible arch section de-

tachably mounted upon the upper edges of the side sections, and a truck on the track for carrying the collapsed arch section therealong and provided with raising and lowering means for the arch sections.

2. In combination in a U shaped mold, a beam extending across the bottom of the form, a lower side section at each end of the beam, detachable connections between the 10 ends of the beam and the lower portions of the side sections, detachable diagonal braces between the beam and the side sections, a track extending across the beam intermediate the braces, a collapsible arch section 15 detachably secured to the tops of the side sections, and means carried by the truck for collapsing the arch sections.

3. In combination in a U shaped mold, a

pair of lower side sections, a series of transverse beams extending across the bottom of 20 the mold and adapted to maintain the lower edges of the side sections spaced apart a fixed distance, detachable bracing means from the beams to the side sections, a track mounted on the beams, a collapsible arch 25 section detachably mounted upon the upper edges of the side sections, and a truck on the track carrying collapsing means for the arch section.

In testimony whereof I have hereunto 30 signed my name in the presence of the two subscribed witnesses.

CHARLES D. McARTHUR.
